SPONGE RUBBER WRISTLET

Henry Flink, Morton, Minn.

Application January 8, 1952, Serial No. 265,464

2 Claims. (Cl. 2—170)

1

This invention relates to apparel adapted to be worn around the arm and more particularly to a wristlet for protecting the forearm against the flow of moisture from the user's hand.

The main object of the invention is to provide a novel and improved wristlet of simple construction which is easy to place on the wrist and which provides efficient protection of the user's forearm against the flow of moisture from the hand, whereby the user's sleeve may be protected against becoming wet.

A further object of the invention is to provide an improved sponge rubber wristlet which is inexpensive to manufacture, which is sturdy in construction, and which is effective in diverting water and moisture from the user's hand so that said water and moisture will not come into contact with the forearm but will instead be diverted from the forearm, enabling the user to wash his hands or to perform other acts bringing his hands into contact with water without risk of wetting his sleeves.

Further objects and advantages of the invention will become apparent from the following description and claims, and from the accompanying drawings, wherein:

Figure 1 is a view of a person's hand and wrist having an improved wristlet device according to the present invention mounted on the wrist.

Figure 2 is a top view of the wristlet device of Figure 1.

Figure 3 is a cross sectional view taken on the line 3—3 of Figure 2.

Figure 4 is a top view showing a modified form of wristlet according to the present invention.

Referring to the drawings, and more particularly to Figures 1 to 3, the wristlet device is designated generally at 11 and comprises a substantially annular body of sponge rubber having a central aperture 12 adapted to receive the person's wrist, shown at 13, the aperture 12 being somewhat smaller in diameter than the average diameter of the person's wrist, whereby the wrist is snugly engaged in the aperture 12 when worn, the body of the wristlet engaging sufficiently tightly around the wrist to form a sealed connection therewith. As shown in Figure 3, the wristlet tapers in thickness from one end thereof to the other, and has a frusto conical surface, shown at 14. When the wristlet is worn, the thickest portion of the wristlet is located adjacent the wearer's forearm and the portion of smallest diameter is located ad-

jacent the person's hand. The main portion of the wristlet device is formed of sponge rubber of relatively coarse texture and the thickest portion of the wristlet device is formed integrally with said main portion but is of relatively fine texture, as shown at 17, the face of the wristlet adjacent the user's forearm, shown at 18, being provided with a relatively smooth finish. When moisture flows from the user's hand onto the wristlet, the moisture is trapped in the relatively coarse-textured forward portion of the wristlet and flow of the moisture over the frusto conical surface 14 is retarded by the cellular surface defined by the coarse-textured sponge rubber. The moisture absorbed in the wristlet is prevented from flowing through the smooth-surfaced face 18 by the flow resistant barrier defined by the fine-textured sponge rubber 17, whereby the moisture is confined to the main body of the wristlet and cannot flow through the smooth-surfaced face 18 onto the user's forearm. Furthermore, in view of the fine texture of the portion of the wristlet adjacent the forearm, said portion is substantially prevented from absorbing moisture and the moisture will mainly be absorbed in the coarse-textured main portion of the wristlet adjacent the user's hand.

To remove moisture from the wristlet, it is merely necessary to squeeze the wristlet, whereby the moisture will be expelled therefrom.

Referring now to Figure 4, a modified form of wristlet according to the present invention is disclosed, said modified form being generally oval in shape and being designated generally at 11'. The wristlet 11' has the central aperture 12, similar to that in the previously described form of the invention and is generally frusto conical in shape, the portions of the device located along the major diameter thereof being provided with the sloping surfaces 14', 14' and the surfaces along the minor diameter of the device being of steeper slope. As in the previously described form of the invention, the wristlet is provided with a rear layer of fine-textured sponge rubber, whereas the main portion of the wristlet is of relatively coarse-textured sponge rubber. The wristlet shown in Figure 4 is employed in the same manner as that shown in Figures 1 to 3, and in order to remove the excess moisture from the wristlet, it is merely necessary to squeeze the thick major portions of the wristlet at the sloping surfaces 14', 14' wherein the moisture is mainly absorbed. As in the previously described embodiment of the invention, the moisture is

prevented from flowing through the smooth-surfaced rear face of the wristlet and is confined to the coarse-textured main portion of the wristlet.

While certain specific embodiments of an improved spong rubber wristlet has been disclosed in the foregoing description, it will be understood that various modifications within the spirit of the invention may occur to those skilled in the art. Therefore, it is intended that no limitations be placed on the invention except as defined by the scope of the appended claims.

What is claimed is:

1. A wristlet for preventing the flow of water from the hand to the forearm comprising a body of sponge rubber having a central aperture adapted to receive the wrist and tapering in thickness from one end thereof to the other, the body being adapted to surround the user's wrist with the thickest portion thereof located adjacent the user's forearm, the sponge rubber of the body adjacent the user's hand being relatively coarse in texture, whereby moisture from the user's hand will be intercepted on the flaring outer portion of said body, and the sponge rubber of the thickest portion of the body being relatively fine in texture, whereby the flow of moisture toward the thickest portion of the body will be retarded.

2. A wristlet for preventing the flow of water from the hand to the forearm comprising a body

5 of sponge rubber having a central aperture adapted to receive the wrist and tapering in thickness from one end thereof to the other, the body being adapted to surround the user's wrist with the thickest portion thereof located adjacent the user's forearm, the sponge rubber of the body adjacent the user's hand being relatively coarse in texture, whereby moisture on the user's hand will be intercepted from the flaring outer portion of said body, and the flow of moisture toward the thickest portion of the body will be retarded, and the thicker end of the body, adjacent the user's forearm being of relatively fine texture sponge rubber and having a smooth finish to substantially limit absorption of moisture by said thicker end and to substantially prevent moisture from flowing through said thicker end to the user's forearm.

HENRY FLINK.
